UNITED STATES PATENT OFFICE

ALBERT G. PERKINS, OF BUFFALO, NEW YORK

APPARATUS FOR COATING PIPES

Application filed May 31, 1930. Serial No. 458,482.

This invention relates to an apparatus which has been designed more particularly for coating or lining the inner walls of pipe lines to prevent the formation of barnacles 5 thereon.

It has for one of its objects to provide an apparatus of this character having novel and efficient means for applying successive coats of an adhesive material and a powder 10 or like dry substance to a pipe-wall in an expeditious and economical manner.

Another object of the invention is to provide means for removing any surplus of the dry substance from the pipe-wall and re- 15 turning it to the feed hopper or container.

The invention has for its further object to provide certain novel features of construction and arrangement of parts herein- 20 after described and particularly pointed out in the appended claims.

In the accompanying drawings:—

Figure 1 is a side elevation of a coating apparatus embodying my invention, the same being shown within a pipe line for 25 treating its interior surface. Figure 2 is a rear view of the apparatus arranged within the pipe. Figure 3 is an enlarged central longitudinal section thereof. Figure 4 is an enlarged cross section taken on line 4—4, 30 Figure 3. Figure 5 is a fragmentary longitudinal section, similar to Figure 3, showing the fluid spray nozzle and associated parts.

Similar characters of reference indicate 35 corresponding parts throughout the several views,

While my invention is applicable in connection with different kinds of work requiring a surface coating, it has been primarily designed for treating the inner walls of water 40 pipe lines with a coating of a fluid adhesive material followed by a covering of cement or like substance, whereby a surface is provided which prevents the formation of barnacles 45 on the wall of the pipe line. To this end the apparatus consists, generally, of a carriage adapted to be propelled through the pipe line, a revolving discharge nozzle constructed to deliver the charge of fluid and cement to the pipe-wall in predetermined sequence, and 50 means for removing any surplus of the ce-

ment or other dry substance from such wall.

Referring now to the drawings, 10 indicates a section of pipe through which my apparatus is adapted to travel for treating or coating the inner wall of the pipe with a 55 protective covering or lining. The carriage of the apparatus may be of any appropriate construction, but preferably consists of a longitudinal frame 11 including front and rear sets of wheels 12, 12 and intermediate 60 sets of wheels 13, the several sets of wheels being driven by an electric or air motor 14 connected by gearing 15, 16 with the driving shaft 17 of either the front or rear sets of wheels 12. Motion is also transmitted to the 65 intermediate sets of wheels and for this purpose a sprocket chain 18 is provided which passes at its ends around sprocket wheels 19 applied to the wheels 12, while its upper and lower stretches engage sprocket wheels 70 20 applied to the intermediate sets of wheels 13. As shown in Figure 1, the front and rear sets of wheels 12 are smaller in diameter than the intermediate sets of wheels 13 so that normally, as the machine travels 75 through the pipe, said front and rear wheels clear the pipe wall, while the intermediate sets of wheels engage the pipe wall, these wheels being preferably provided with a 80 rubber or like tread surface.

Surmounting the frame 11 is a platform 21 which is preferably so mounted that it can be adjustable vertically relatively to the frame. For this purpose it carries depending legs or posts 22 which telescopically engage 85 tubular members 23 applied to said frame. The platform is held in any desired set position relative to the frame by set screws 24 or other equivalent means. Disposed centrally of the platform adjacent the rear end thereof is a longitudinally extending tubular member or revolvable head 25 journaled at its ends in bearings 26 and provided at its rear end with a spraying device or applicator indicated generally by the numeral 27. This 90 tubular member is designed to receive the materials to be sprayed and thence deliver them under pressure to the revolving spraying device 27, which is designed to discharge 95 the materials successively and in proper 100 sequence.

quence to the pipe wall as the machine travels through it. To this end, the member 25 is provided with a centrally disposed conduit or chamber 28 for receiving a charge of cement or like substance, the front or inlet end of this conduit opening into the lower end of a feed hopper or receptacle 29 containing a supply of cement, and the latter being conveyed from the hopper through the conduit 10 by a feed screw 30 which extends lengthwise through said parts, as seen in Figure 3. Communicating with the discharge end of this conduit and radiating from the revolving member 25 is a sectional nozzle or discharge tube 31 into which the cement is delivered from the conduit and thence discharged from its mouth on to the pipe wall. The feed screw may be driven by an electric or air motor 32 through the medium of a pinion 33 and gear 34. As shown in Figure 3, the sections of this nozzle are telescopically joined and the outer section carries a guide roller or gage wheel 35 which is disposed for rolling contact with the inner wall of the pipe 10 and should there be any unevenness in the pipe, a coil spring 36 interposed between the nozzle sections will permit the outer section to move radially outward and will constantly maintain the discharge mouth of the nozzle in proper relation to the pipe wall. This gage wheel also governs the thickness or the amount of cement applied to the pipe by maintaining the nozzle mouth at a predetermined distance from the inner surface of the pipe.

35 Formed in the member 25 and surrounding the cement conduit 28 thereof are a plurality of concentric chambers or passages 37, 38 and 39. The chamber 37 is adapted to receive a supply of fluid adhesive material, the chamber 38 is adapted to communicate with a source of air pressure which is employed for spraying the fluid material on to the pipe wall, and the chamber 39 is adapted to communicate with a source of suction which is utilized to remove any surplus of cement applied to the pipe. The fluid material is applied to the pipe through the medium of a nozzle 40 disposed radially adjacent to the cement nozzle 31 and containing a passage 41 communicating at its inner end with the fluid compartment 37 and also containing an air passage 42 communicating at its inner end with the air compartment 38 of the member 25, air being introduced from the last-named chamber into the air tube through a port 43 arranged adjacent the inner end of the nozzle. It will be noted from Figure 5, that the air passage 42 terminates short of the outer end of the nozzle to create a suction effect in the fluid passage 41 and thereby accomplish a spraying action of the fluid as it is discharged from the nozzle. The vacuum chamber 39 communicates at its outer or rear end with a radial tube or nozzle 44 applied to the revolving member 25 and having its discharge

end disposed close to the pipe wall. I have shown two of such suction nozzles in the drawings, which are disposed substantially at right angles to each other and at right angles to the cement nozzle 31 and the fluid nozzle 41, respectively, as shown in Figure 2. These several nozzles are otherwise so disposed, that, during the revolution of the member 25, the nozzle 40 will first spray the fluid adhesive on to the pipe wall, after which the cement will be applied to the adhesive coating from the nozzle 31, and finally the vacuum nozzle or nozzles 44 will act to remove any surplus of cement from the pipe wall and return it to the point of supply.

80 Mounted on the front end of the machine alongside the cement hopper 29 is a tank 45 which contains a supply of fluid adhesive or equivalent material. The upper end of this tank has a filling pipe 46 and opening into the lower end of the tank is an outlet or discharge pipe 47 leading to the fluid chamber 37 in the member 25. This fluid may be forced from the tank to its chamber by air pressure, an air pipe 48 being shown connected to the tank for this purpose. A branch 49 of this air pipe leads to the air chamber 38 and is employed for spraying the fluid issued from the nozzle 31. The vacuum employed for removing any surplus cement from the pipe wall may be derived from a suction fan or like device, not shown, the suction pipe 50 of the latter being preferably connected to the upper end of the cement receptacle 29 and leading from the same is a vacuum pipe 51 communicating at its other end with the chamber 39 in the member 25. By this arrangement as the suction nozzle 44 picks up any surplus material from the pipe wall it is conveyed through the nozzle to the chamber 39 and thence through the pipe 51 back to the receptacle 29.

100 The means for establishing communication between the pipes 47, 49 and 50 and the corresponding chambers 37, 38 and 39 of the revolving head 25 are substantially the same and a description of one will suffice for the others. This connection preferably consists of a distributing collar 52 surrounding the revolving head and having an internal annular groove 53, the chambers 37, 38 and 39 being provided with inlet ports 54, 55 and 56, respectively, which communicate with the surrounding groove of the corresponding distributing collar 52, as seen in Figures 3 and 5. To prevent leakage of the fluid between the distributing collar and the contiguous wall of the revolving member 25, packing glands 57 are screwed into opposite ends of said collar.

110 In order to loosen any surplus cement applied to the pipe-wall, I preferably provide one of the vacuum nozzles 44 with effective means for accomplishing this result. These means may consist of a rubber or like flex-

ible agitator brush 58 applied to the leading side of the nozzle and a yieldable wiper 59 of rubber or like material applied to the trailing side of the nozzle. By this construction the brush loosens and breaks up any surplusage of the cement to enable the suction nozzle to readily pick it up, while the wiper smooths the cement coating evenly over the path of travel of the nozzle.

10 It is to be understood that my invention is not limited to the exact details of construction and arrangement of parts herein shown and described, and that various changes therein and modification thereof may be made within the scope of the appended claims 15 without departing from the spirit of the invention or sacrificing any of its advantages.

I claim as my invention:—

1. An apparatus for lining pipe-walls, 20 comprising a revolving member including a central conduit in communication with a source of coating material and a chamber for receiving a fluid adhesive material, discharge nozzles in communication with said conduit and said chamber for applying said materials to the pipe-wall in succession one over the other, means arranged within said conduit for forcing the coating material bodily through its nozzle and depositing it 25 on the pipe-wall, and means for delivering the fluid material from its nozzle in substantially the form of a spray.

2. An apparatus for lining pipe-walls, 30 comprising a revolving member including a central conduit in communication with a source of coating material and a chamber for receiving a fluid adhesive material, discharge nozzles applied to said revolving member to turn therewith and disposed in different radial positions, one of said nozzles including 35 an air tube for effecting the spraying of the fluid material on to the pipe-wall, means arranged within said conduit for forcing the coating material bodily through its nozzle and depositing it on to the fluid-surfaced 40 pipe-wall, and means for effecting the removal of any surplus of coating material 45 from said pipe-wall.

3. An apparatus for lining pipe-walls, 50 comprising a chambered member for receiving independent charges of coating materials, one of the materials being substantially in the form of a fluid adhesive and the other being a substantially dry substance, revolving nozzles in communication with said chambered member for applying the materials, respectively, to the pipe-wall in predetermined sequence, and means for removing any surplusage of the dry material from the 55 pipe-wall.

4. An apparatus for lining pipe-walls, 60 comprising a chambered member for receiving independent charges of coating materials, one of the materials being substantially in 65 the form of a fluid adhesive and the other

being a substantially dry substance, revolving nozzles in communication with said chambered member for applying the materials, respectively, to the pipe-wall in predetermined sequence, said member having a third chamber adapted for communication with a source of vacuum, and a revolving nozzle connected to said third chamber and disposed with its mouth in opposing relation to the pipe-wall to remove any surplusage of the dry coating 75 substance therefrom.

5. An apparatus for lining pipe-walls, comprising a chambered member for receiving independent charges of coating materials, one of the materials being substantially in 80 the form of a fluid adhesive and the other being a substantially dry substance, revolving nozzles in communication with said chambered member for applying the materials, respectively, to the pipe-wall in predetermined sequence, said member having a third chamber adapted for communication with a source of vacuum, a revolving nozzle connected to said third chamber and disposed with its mouth in opposing relation to the 85 pipe-wall to remove any surplusage of the dry coating substance therefrom, and means on said last-named nozzle for loosening such surplusage from the pipe-wall.

6. An apparatus for lining pipe-walls, 90 comprising a chambered member for receiving independent charges of coating materials, one of the materials being substantially in 95 the form of a fluid adhesive and the other being a substantially dry substance, revolving nozzles in communication with said chambered member for applying the materials, respectively, to the pipe wall in predetermined sequence, said member having a third chamber adapted for communication with a source of vacuum, a revolving nozzle connected to said third chamber and disposed with its mouth in opposing relation to the pipe-wall to remove any surplusage of the 100 dry coating substance therefrom, 105 an agitator applied to the leading edge of said last-named nozzle-mouth for loosening such surplusage from the pipe-wall, and a wiping device applied to the trailing edge of said nozzle-mouth and engaging the coated surfaces of said pipe-wall.

7. An apparatus of the character described, comprising a revolving member including a plurality of chambers for receiving independent charges of a fluid adhesive material, a dry substance, and air under pressure, radial nozzles projecting from said member and in communication with said respective chambers for applying the adhesive and the dry substance successively to a pipe-wall, the nozzle for applying the adhesive fluid containing an air tube connected to said air chambers for spraying the fluid on to the pipe-wall, and means for forcing the dry substance through 110 115 120 125 130

its chamber and thence through the nozzle on to the fluid-coated pipe-wall.

8. An apparatus of the character described, comprising a revolving member including a plurality of chambers for receiving independent charges of a fluid adhesive material, a dry substance, and air under pressure, said member also having a fourth chamber adapted for communication with a source of vacuum, 10 radial nozzles projecting from said member and in communication with said respective first-named chambers for applying the adhesive and the dry substance successively to a pipe-wall, the nozzle for applying the fluid 15 containing an air tube connected to said air chamber for spraying the fluid on to the pipe-wall, means for forcing the dry substance through its chamber and thence through the nozzle on to the fluid-coated pipe-wall, and a 20 nozzle in communication with said vacuum chamber and disposed to remove any surplusage of the applied dry substance from the pipe-wall.
